UNITED STATES PATENT OFFICE.

GEORGES CHAUMET, ALSO KNOWN AS GUY DE VADIMON, OF PARIS, FRANCE.

DESIGN FOR A BRACELET.

Application filed September 22, 1927, Serial No. 23,508, and in France August 2, 1927. Term of patent 3½ years.

To all whom it may concern:

Be it known that I, GEORGES CHAUMET, dit GUY DE VADIMON, a citizen of the French Republic, residing at Paris, in the Republic of France, have invented a new, original, and ornamental Design for Bracelets, of which the following is a specification, reference being had to the accompanying drawing, forming part thereof.

Fig. 1 is a view of my bracelet opened out to better show the ornamental features thereof; and

Fig. 2 is a view of the same bracelet in closed position showing the ornamental aspect thereof in that position.

I claim:

The ornamental design for a bracelet, as shown.

In testimony whereof, I have signed my name to this specification at Paris, France, this 3rd day of September, 1927.

GEORGES CHAUMET,
Dit Guy de Vadimon.
